WIRE MANIPULATING TOOL

Samuel S. Colt, Orange, N. J.

Substitute for abandoned application Serial No. 410,016, November 27, 1929. This application August 18, 1936, Serial No. 96,641

13 Claims. (Cl. 140—118)

This invention relates, generally, to an improved tool for manipulating wire; and the invention has reference, more particularly, to a novel tool for twisting and tightening wire ties. 5 The present application is a substitute for my previous forfeited application for United States Letters Patent Ser. No. 410,016, filed November 27th, 1929.

This invention has for its principal object to 10 provide a novel tool for engaging and twisting together the end portions of wire ties, whereby such ties are tautly drawn about or in assembled connection with bodies or parts to be bound thereby. The novel tool, adapted to so function, 15 may be usefully employed for many purposes, but is especially useful as a means for tightening and securing wire ties employed in assembling parts of concrete pouring forms, in assembling parts of building structures, and in various similar fields. 20 The invention has for a further object to provide a novel tool for the purposes described, comprising in combination a lever bar having means to receive and engage wire ends to apply twisting motion thereto when the lever bar is turned 25 about its center, and a locking bar rotatably related to said lever bar, having means cooperative with the latter to dispose and grip the wire ends against slip when the wire is subjected to twisting movement. 30 Other objects of this invention, not at this time more particularly enumerated, will be clearly understood from the following detailed description of the same.

An illustrative embodiment of this invention 35 is shown in the accompanying drawings, in which:—

Fig. 1 is a top plan view of the tool of this invention; Fig. 2 is a bottom plan view of the same; Fig. 3 is a longitudinal sectional view of the same; 40 and Fig. 4 is a horizontal section, taken on line 4—4 in Fig. 3.

Fig. 5 is a front elevation showing the initial 45 application of the tool of this invention to the ends of tie-wires of a concrete pouring form preparatory to engaging and twisting said wires; and Fig. 6 is a vertical section taken on line 6—6 in Fig. 5, the tool being shown in side elevation.

Fig. 7 is a front elevation showing the tool 50 operatively engaged with the tie-wire ends and in the act of twisting the same together; and Fig. 8 is a vertical section, taken on line 8—8 in Fig. 7, the tool being shown in side elevation.

Similar characters of reference are employed 55 in the above described views, to indicate corresponding parts.

Referring to said drawings, the reference character 10 indicates a lever-bar having oppositely and longitudinally extending handles 11. Secured to the central portion of said lever-bar to project laterally outward therefrom is a hub-

sleeve 12. Said hub-sleeve and lever bar possess a through opening or bore 13. Said lever bar is preferably provided, on one face thereof, with longitudinally disposed ribs 14, the same being laterally spaced to provide a seat for a die-member 15. Said die-member 15 has a central opening 16, whereby the same may be engaged over said hub-sleeve 12. Said die-member 15 is further provided with longitudinally spaced die-openings 17, respectively on opposite sides of said central opening 16. Said lever-bar is provided with openings 18 corresponding to and with which said die-openings 17 register. The die-member 15 is preferably made of hardened steel. 5

While it is preferred to employ the separable 15 die-member 15, it is nevertheless not essential so to do, particularly in smaller sizes and cheaper grades of the tool, since, in the latter case, the openings 18 of the lever-bar may serve as die-openings, and the die-member 15 may be omitted. 20 The construction so modified is deemed to be and intended to be within the scope of the instant invention.

Rotatably mounted on said hub-sleeve 12 of lever-bar 10 is a locking bar 19 also provided with oppositely and longitudinally extending handles 20. Preferably said locking bar 19 is spaced away from said lever-bar 10, and to this end one or more spacing washers 21 are engaged on said hub-sleeve 12, intermediate said bars 10 and 19. 25 The outer or free end portion of said hub-sleeve 12 is screw-threaded to receive a keeper nut 22 to retain said locking bar and lever-bar in mutually cooperative assembled relation. Provided in one side margin of said locking bar 19, radially 30 disposed from the common axis of rotation of said locking bar and lever bar at a distance substantially equivalent to the distance of one die-opening 17 from such axis of rotation, is a shoulder 23. A similar shoulder 24 is provided in the opposite margin of said locking bar 19; the same being similarly disposed relative to the other or opposite die-opening 17 of said lever-bar. Secured to the locking-bar to project from the under side thereof, and substantially aligned 35 respectively to the respective shoulders 23 and 24, are abutment pins 25. Said locking bar is further provided at each side thereof, and longitudinally spaced from the respective shoulders 23 and 24, with laterally projecting outwardly off-set 40 wedge wings 26 having chamfered inner margins 27. 45

For convenience in initially bending wire into U-shaped ties adapted to embrace two or four inch form framing members, gauge studs 28 are 50 provided for fixed projection from the outer face of said locking bar 19. Certain of said studs 28 are disposed substantially four inches apart longitudinally of the locking bar, while others there-of are disposed substantially two inches apart 55 60

laterally of the locking bar. Cooperative with the gauge studs 28 is a stop stud 29. If it is desired to form a U-shaped wire tie of substantially four inch width, straight wire of desired length 5 is laid behind the longitudinally spaced gauge lugs 28 and in front of the stop lug 29, whereupon the oppositely projecting end portions of the wire may be bent forward by hand to produce the U-shape tie of desired width. In like 10 manner, if it is desired to form a U-shaped wire tie of substantially two inch width, straight wire of desired length is laid behind the laterally spaced gauge lugs 28 and in front of the stop lug 29, whereupon the oppositely projecting end portions 15 of the wire may be bent outwardly by hand to produce the U-shaped tie of such desired width.

Illustrative of one use of the novel wire manipulating tool of this invention, I have shown, in 20 Figs. 5 to 8 inclusive of the drawings, the application of the tool to U-shaped wire ties 30 employed to bind together the frame or batten members 31 and sides 32 of a concrete pouring form. In such case the frame or batten members 31 are disposed against exterior faces of the form sides 32, the latter being spaced apart by intermediate spacer struts 33. The wire tie 30 is disposed to embrace one frame or batten member, extending therefrom through the sides and interior of the form, with the ends thereof engaged about the other frame or batten member. Preferably a heavy nail, short length of relatively stiff wire or similar rod-like element 34 is disposed to project outwardly from the outer face 25 of the last mentioned frame or batten member, and the free end portions 30' of the wire tie are loosely twisted around the same by hand, and thus disposed ready for the application of the tool thereto.

40 To operatively apply the tool to the wire tie end portions 30', the element 34 is inserted through the central bore or through opening 13 of the lever-bar and its hub-sleeve. With the locking lever 19 swung or turned to an angular position whereby the die-openings 17 are exposed, the wire tie end portions 30' are respectively entered through the respective die-openings 17 to extend therethrough, as shown in Figs. 5 and 6. When the tool has been thus initially applied to 45 the element 34 and wire tie end portions 30', the locking bar 19 is turned (in the direction of the arrow in Fig. 5), thereby carrying the shoulders 23 and 24 respectively into engagement with the projecting wire tie end portions (as is shown in Figs. 5 and 6). The turning of the locking bar 19 is thereupon continued until the same is brought into longitudinal alignment with the lever bar 10. This continued movement of the locking bar 19 relative to the lever bar, acts 50 upon the projecting wire tie end portions 30', through the engaging shoulders 23 and 24, to bend over the same exteriorly of the die-openings 17 and into abutment with the abutment pins 25, thereby gripping or snubbing the wire ends 55 against lengthwise slip relative to the die openings 17.

Upon accomplishment of the above described operations, the user grasps the parallel handle portions of both bars 10 and 19, and turns the 70 entire tool about the central axis thereof and in the direction of the arrow shown in Fig. 7. The effect of this movement is to produce a twisting movement of the wire tie end portions about the element 34, thereby both drawing tight the 75 stretches of wire extending around the frame or

batten members and through the form, to bind the form sides and spacers tightly together in assembled relation, while also securing the ends of the wire tie together. The advantage of using the element 34 is that it provides a core about 5 which the twisted convolutions of the wire tie ends may form, thus eliminating risk of kinking the wire with resultant likelihood of breakage thereof, and consequently permitting the wire tie to be drawn to maximum tautness quickly, safely, and efficiently. It will be understood, however, that the use of the core element 34 is optional, and that in many cases the wire tie ends may be directly intertwined together by the operation of the tool, since the wire twisting function 10 of the tool is operative whether such core element is present or not.

After the wire tie end portions 30' have been twisted and secured together in the manner above described, the user turns the locking lever relative to the lever bar in a direction opposite to that of the arrow shown in Fig. 5. Such movement of the locking lever carries the wedge wings 26 so that their chamfered margins 27 slide beneath the bent over end portions 30' with lifting 20 effect thereon so that the same are upbent back to normal substantially straight outward extension from the die-openings 17, whereupon the tool may be drawn outwardly and away from the said end portions and the element 34, and thus 25 removed from the finished work.

One end of a handle 20 of locking bar 19 is provided with a bifurcate slotted portion 35. This end portion may be engaged with the projecting ends of the wire tie and element 34, and manipulated to turn or bend inward toward the 30 face of the form wall such projecting ends.

From the above description it will be obvious that the tool of this invention affords a quick 40 acting and powerful aid for the purposes intended.

As many changes could be made in the above construction and many apparently widely different embodiments of this invention could be made without departing from the scope thereof, it is intended that all matter contained in the above 45 description or shown in the accompanying drawings shall be interpreted as illustrative and not in a limiting sense.

I claim:—

1. A tool of the kind described, comprising a 50 lever bar having spaced openings for the extension therethrough of wire end portions desired to be twisted together, a locking bar rotatably connected with said lever bar, and said latter bar having means to engage and bend projecting parts of said wire end portions against withdrawal from said lever bar openings.

2. A tool of the kind described, comprising a lever bar having a central hub portion, said lever bar having openings respectively spaced 55 therein on opposite sides of said hub portion for the extension therethrough of wire end portions desired to be twisted together, a locking bar rotatably mounted on said hub portion over said lever bar, and said locking bar having means to engage and bend projecting parts of said wire end portions against withdrawal from said lever bar openings.

3. A tool of the kind described, comprising a 70 lever bar having a central hub portion, said lever bar having openings respectively spaced therein on opposite sides of said hub portion for the extension therethrough of wire end portions desired to be twisted together, a locking bar ro- 75

tatably mounted on said hub portion over said lever bar, and said locking bar having marginal shoulders to bend over projecting parts of said wire end portions when said locking bar is turned relative to and into alignment with said lever bar, and abutment means carried by said locking bar to engage said bent wire end portions, all whereby the latter are held against withdrawal from said lever bar openings.

10. 4. A tool of the kind described, comprising a lever bar having a central hub portion, said lever bar having openings respectively spaced therein on opposite sides of said hub portion for the extension therethrough of wire end portions desired to be twisted together, a locking bar rotatably mounted on said hub portion over said lever bar, said locking bar having means to bend over projecting parts of said wire end portions when said locking bar is turned in one direction relative to and into alignment with said lever bar, and said locking bar having additional means to engage and bend back to initial position said bent wire end portions when said locking bar is turned in the opposite direction relative to said locking bar.

5. A tool of the kind described, comprising a lever bar provided with a central hub sleeve having a through opening to receive a core element, said lever bar having openings respectively spaced therein on opposite sides of said hub sleeve for the extension therethrough of wire end portions desired to be twisted together around said core element, a locking bar rotatably mounted on said hub sleeve over said lever bar, said locking bar having means operative on rotation thereof in one direction relative to said lever bar to engage and bend projecting parts of said wire end portions against withdrawal from said lever bar openings, and said locking bar having additional means operative on rotation thereof in the opposite direction relative to said lever bar to engage and bend back said bent wire end portions to initial projecting positions.

6. A tool of the kind described, comprising a lever bar having a central hub portion, means on said lever bar providing a die-member seat, a die-member receivable in said die-member seat, said die-member having die-openings for the extension therethrough of wire end portions desired to be twisted together, a locking bar rotatably mounted on said hub portion, and said locking bar having means to engage and bend projecting parts of said wire end portions against withdrawal from said die-openings.

55. 7. A tool of the kind described, comprising a lever bar having a central hub portion, means on said lever bar providing a die-member seat, a die-member receivable in said die-member seat, said die-member having die-openings for the extension therethrough of wire end portions desired to be twisted together, a locking bar rotatably mounted on said hub portion, said locking bar having means operative on rotation thereof in one direction relative to said lever bar to engage and bend projecting parts of said wire end portions against withdrawal from said die-openings, and said locking bar having additional means operative on rotation thereof in the opposite direction relative to said lever bar to engage and bend back said bent wire end portions to initial projecting positions.

8. A tool of the kind described, comprising a lever bar provided with a central hub sleeve having a through opening to receive a core element, means on said lever bar providing a die-member seat, a die-member receivable in said seat, said die-member having die-openings for the extension therethrough of wire end portions desired to be twisted together, a locking bar rotatably mounted on said hub sleeve over said sleeve bar, said locking bar having marginal shoulders to bend over projecting parts of said wire end portions when said locking bar is turned relative to and into alignment with said lever bar, and abutment means carried by said locking bar to engage said bent wire end portions.

9. A tool of the kind described, comprising a lever bar provided with a control hub sleeve having a through opening to receive a core element, means on said lever bar providing a die-member seat, a die-member receivable in said seat, said die-member having die-openings for the extension therethrough of wire end portions desired to be twisted together, a locking bar rotatably mounted on said hub sleeve over said lever bar, said locking bar having marginal shoulders to bend over projecting parts of said wire end portions when said locking bar is turned in one direction relative to and into alignment with said lever bar, abutment means carried by said locking bar to engage said bent wire end portions, and wedge wings connected with said locking bar operative on rotation of the latter in the opposite direction relative to said lever bar to engage and bend back said wire end portions to initial projecting positions.

10. In a tool for the purposes described, a lever bar having spaced openings for the extension therethrough of wire end portions desired to be twisted together, and means movably related to said lever bar for engaging and retaining said wire end portions against withdrawal from said openings.

11. In a tool for the purposes described, a lever bar having spaced openings for the extension therethrough of wire end portions desired to be twisted together, and manipulatable means carried by said lever bar to bend said wire end portions relative to said lever bar to retain same against withdrawal from said openings thereof.

12. In a tool for the purposes described, a lever bar having spaced openings for the extension therethrough of wire end portions desired to be twisted together, means movably related to said lever bar for engaging and retaining said wire end portions against withdrawal from said openings, and said lever bar having an opening intermediate said first mentioned openings to receive a core about which said wire end portions are twisted.

13. In a tool for the purposes described, a lever bar having spaced openings for the extension therethrough of wire end portions desired to be twisted together, manipulatable means carried by said lever bar to bend said wire end portions relative to said lever bar to retain same against withdrawal from said openings thereof, and said lever bar having an opening intermediate said first mentioned openings to receive a core about which said wire end portions are twisted.

SAMUEL S. COLT.
